OR D. 3,303

Nº 3303

Arthur Stafford

Design for Key Tags &c.

PATENTED
DEC 29 1868

Arthur Stafford

Witness,

Geo. W. Nichols
Chas. Smith

ARTHUR STAFFORD, OF BROOKLYN, NEW YORK.

Design No. 3,303, dated December 29, 1868.

DESIGN FOR A KEY-TAG.

The Schedule referred to in these Letters Patent and making part of the same.

To all whom it may concern:

Be it known that I, ARTHUR STAFFORD, of Brooklyn, in the county of Kings, and State of New York, have invented or produced a certain new and original Design for Tags for Keys, &c.; and I do hereby declare the following to be a full and correct description thereof, reference being had to the annexed drawing, making part of this specification, in which an elevation of said tag is shown.

The general shape of said tag is that of a shield with a beaded edge.

The background of the surface ornamentation is formed by lines having stars, 2, and ribs, 3, in imitation of an American shield.

An eagle, 4, with its wings spread, is in the shield, and across this streamers or ribbons, 5, are wound.

By impressing the surface ornamentation, 2, 3, and 4, the streamers 5 are left in low relief, to form spaces for receiving engraved names, addresses, &c.

A ring, 6, is formed at the upper central part of the shield.

What I claim, and desire to secure by Letters Patent, is—

The design of the ornamentation for the surface of the tag, substantially as represented in the drawing.

Dated this 25th day of November, A. D. 1868.

ARTHUR STAFFORD.
